Patented Feb. 10, 1920.

UNITED STATES PATENT OFFICE.

JOHANN G. PETERSON, OF JERSEY CITY, NEW JERSEY.

ELECTRIC SWITCH

1,330,390.

Specification of Letters Patent.

Patented Feb. 10, 1920.

Application filed December 6, 1917. Serial No. 205,863.

To all whom it may concern:

Be it known that I, JOHANN G. PETERSON, a citizen of the United States, residing at Jersey City, in the county of Hudson and State of New Jersey, have invented certain new and useful Improvements in Electric Switches, of which the following is a specification.

This invention relates to electric switches. While the improvements, and there are several, are susceptible of incorporation with utility in switches of different kinds, they are of prime advantage, however, when embodied in a pendent switch. Among the objects of the invention are the provision of an article of the character set forth which is simple in construction, quite compact, and positive and certain in action. The device comprises other features of novelty which with the foregoing will be stated at length in the following description, wherein I will set forth in detail that form of embodiment of the invention which I have selected for illustration in the drawings accompanying and forming part of the present specification. I do not necessarily limit myself to this particular disclosure; I may depart therefrom in several particulars within the scope of the invention defined by the claims following said description.

Referring to said drawings:

Figure 1 is an elevation of a switch comprising the invention.

Fig. 2 is a vertical transverse sectional view of the same.

Figs. 3 and 4 are sections on the line 3—4 of Fig. 2, looking respectively toward the left and the right.

Fig. 5 is a detail of the switch mechanism. Fig. 6 is a horizontal sectional view of the same on the line 6—6 of Fig. 5, looking in the direction of the arrows, the actuator however being shown in elevation.

Fig. 7 is a vertical section on the line 7—7 of Fig. 3, looking in the direction of the arrow.

Like characters refer to like parts throughout the several views which are on different scales.

The appliance includes in its structure a suitable supporting body such as that denoted in a general way by 2. This supporting body is preferably of insulating material

for instance one of the plastic compositions common in the art. As shown it comprises 55 the virtually duplicate sections 3 and 4 which when in assembled relation fit flatwise against each other as shown for instance by Figs. 1 and 2. The two parts 3 and 4 may be united together in any desirable manner. 60 For this purpose I have shown the screws 5, two of them generally being provided and being superposed, the section 4 having bores as 6 for the passage of the screws and the section 3 having internally threaded sleeves 65 7 ordinarily molded therein, to receive the threaded portions of the screws and thus hold the two parts 3 and 4 in assembled relation. It becomes a simple matter to separate the parts, and this is accomplished by 70 backing out the two screws to the requisite extent. The heads of the screws 5 are ordinarily countersunk in the body section 4.

While either of the sections of the supporting body may be equipped with wire 75 connecting and contact means, the part 3 in the structure illustrated is thus provided, and I will now set forth how this is done. Said part 3 has as shown a chamber or compartment 8 into which the complementary 80 apertures 9 open, the upper opening 6 to which I have already referred, extending through the web 10 between these apertures 9. In the apertures 9 are disposed the plates 11 which in the present case do not engage 85 directly against the bottoms of the apertures as I will hereinafter explain. These plates 11 are perforated to freely receive the screws 12, which are threaded into sleeves 13 molded in the composition of the part 3, the inner 90 terminals of the sleeves 13 being expanded as at 14 to anchor the sleeves firmly in place. The outer faces of the sleeves are in the plane practically of the bottoms of the apertures, the plates practically extending into 95 the chamber 8. Between the plates 11 and the bottoms of the apertures 9 are disposed the comparatively thin plates 15 which extend down into the chamber or cavity 8 and which are provided with offsets 16 acting as 10 convenient contacts to be bridged by the switching member of whatever character it may be. The contact plates 15 are perforated to receive the screws 12, and they fit under the wire connecting plates 11 which 10 clamp them respectively as a consequence to

the bottoms of the apertures 9 and chamber or cavity 8. The wire connecting plates 11 have tapped openings to receive the screws 17 which extend through perforations in the 5 respective contact plates 15 and into sockets 18 in the part or section 3. Thus the contact plates 15 are in electrical connection with the respective wire connecting plates 11. The wires 18' extend through an opening 19 in the top of the body 2 and are wrapped or coiled one or more times about the bodies 10 of the screws 17 which bind the bared parts of the wires against the plates 11. In view of this circumstance, it will be clear that 15 when the contact plates 15 are bridged by the electrical connection of the spring fingers or contacts 16, the switch will be in the on relation. This condition is shown in fact by dotted lines in Fig. 2.

20 The switching mechanism includes in its organization a support such as that denoted in a general way by 20. This support or bracket has a body 21 practically flat from the ends of which are the pendent projections or flanges 22 and 23, the flange or projection 22 being a trifle longer than or deeper than the companion projection and fitting an aperture 24 extending from the chamber or cavity 8. The attaching flange 25 20 as shown is perforated to receive the screw 25 in threaded engagement with the sleeve 26 molded into the section 3, the inner end of the sleeve being expanded or spread as described in connection with the 30 sleeve 13. The outer face of the sleeve 26 is practically flush with the aperture 24, and it will be clear that the head of the screw 25 binds the flange or foot 22 solidly and substantially against the bottom of the 35 aperture, the side walls thereof preventing tip of the flange or foot 22 and hence of the support or bracket 20. The section 4 of the body has a chamber or cavity 8' complementary to the cavity or chamber 8 and from 40 the cavity 8' there extends the aperture 24' against the back of which the flange or foot 22 flatwise bears, the lower edges of the flanges 22 and 23 being contiguous to the bottoms of the apertures 24 and 24'. From 45 the aperture 24 extends the recess 26' and through this projects the lower screw 5 which I have already described, the solid portion of the member or part 4 closing this recess 26' and the lower portion of the aperture 24.

55 The switching member is denoted in a general way by 27 and practically speaking it is of bail or inverted form, its sides having at their lower ends the outwardly projecting pintles 28 which fit openings 29 in the cheeks 30 which rise from the base 21 and necessarily form a part of the support or bracket 20. The switching member 27, therefore, rocks between the cheeks 30 which 60 are provided at their sides with extensions

31 provided with inward projections 32, said projections constituting suitable stops to arrest the switching member when in the on and the off positions. In Fig. 5 the switching member is shown in the off position and 70 at this time abuts against the two projections 32 on the right. When in the on position as shown by dotted lines in Fig. 2, the switching member will be against the co-operating projections 32 at the left in said 75 Fig. 5.

The actuator for the switching member is denoted in a general way by 33 and it comprises a body as 34 and buttons as 35. The body 34 is of yoke-form, and it consists as 80 illustrated of a main portion provided with upwardly extending terminals which have threaded holes to be engaged by the screws 36, the shanks of which are molded in and the threaded parts of which extend inwardly from the buttons to fit the said threaded holes at which time the inner ends of the buttons will practically solidly engage the upstanding portions of the connecting or yoke-like body 34. The actuator 90 33 is carried for sliding movement by the support or bracket 20 which has a slot as 37 entirely across to provide for the guide connection of the body 34 with said support, the base 21 having flanges 38 extending toward each other and overlying the bottom or main portion of the body 34 to thus accurately guide said body which forms a rigid part of the actuator 33 in its respective movements. This also provides a 100 proper way of connecting the actuator 33 with its support 20.

The transverse portion of the switching member 27 is provided practically centrally thereof with a depending projection 39 to 105 which is connected one end of the coiled spring 40, the other end of said spring being connected with the loop 41 staked from the main or bottom portion of the body 34. The transverse portion of the spring in addition has the complementary contacting portions 42 on the upper portions of its sides. The sections 3 and 4 of the body of the switch have perforations or openings as 43 to receive the buttons 35, the two openings 43 being coaxial and their inner portions receiving the upstanding parts of the main portion 34 of the actuator when in the respective positions thereof.

In Fig. 2 the full lines show the parts in 120 the off position. To close the circuit, the following procedure will be adopted: The button 35 on the right will be pushed toward the left, thereby carrying the spring 40 therewith, and when the point of connection of said spring with the actuator crosses the dead center position, the spring being under maximum stretch at this time, will instantly snap the switching member 125 27 to the on or dotted line position so as to 130

carry the contact portions 42 between the two spring contacts 43 as shown practically by dotted lines in Fig. 2. To open the circuit the action just described will be reversed.

What I claim is:

1. An article of manufacture for use in switches, comprising a bracket having a base provided with pendent flanges, the bracket having a slot extending through the base and the upper portions of the flanges, an actuator comprising a body provided with buttons at its terminals, the body being fitted in said slot for back and forth movement and the base being provided with side flanges overlying the body of the actuator, a switching member supported by the bracket for oscillation, and a spring connected with the switching member and with the actuator approximately centrally of the length thereof.
2. An article of manufacture for use in switches, comprising a bracket furnished with a base having a slot extending therethrough, an actuator comprising a body provided with buttons at its terminals, the body being fitted in said slot and flatwise engaging the base for back and forth movements, the base being provided with flanges extending from the walls of said slot and which overlie the body of the actuator, a switching member supported by the bracket for oscillation, and a spring connected with the switching member and with the actuator.
3. A switch of the class described comprising a body in sections, a bracket in the body, having a base provided with a pendent flange fastened to one section of the body, the bracket having a slot extending through the base and through the flange thereof, an actuator comprising a body, extending through the sections of the first mentioned body and provided with buttons at its terminals, the body of the actuator being fitted in said slot for back and forth movement, and the base being provided with side flanges overlying the body of the actuator, a switching member supported by the bracket, for oscillation, and a spring connected with the switching member and with the actuator approximately centrally of the length thereof.
4. A switch of the class described comprising a body, a bracket in the body, provided with cheeks having openings, a yoke-like switching member disposed between said cheeks and its branches being provided with integral lateral pivot portions, the cheeks having openings to receive said pivot portions, an actuator movable back and forth between the cheeks, and a coiled spring connected to the switch member and also to the actuator the spring being conditioned by the actuator on each movement thereof to impart a snap movement to the switching member.
5. A switch of the class described comprising a body in sections, means for removably connecting said sections together, a bracket in the body, connected with only one of the sections of the body, the bracket being furnished with a base having a slot extending therethrough, an actuator comprising a body provided with buttons at its end extending through the sections of the switch body, the body of the actuator being fitted in said slot for back and forth movement and the base being provided with holding down means for overlying the body of the actuator, a switching member supported by the bracket for oscillation, and a spring connected with the switching member and with the actuator approximately centrally of the length thereof.
6. A switch of the class described comprising a body in sections, means for detachably connecting said sections with each other, a bracket in the body connected removably solely with one of the sections of the body, a switching member supported by the bracket, an actuator for the switching member also supported by the bracket, and a spring for imparting a snap movement to the switching member, and connected with the switching member and the bracket, the spring being conditioned to snap the switching member by the actuator, the bracket, the actuator, the switching member and the spring being removable from that section of the body with which said bracket is connected, as a unit.
7. A switch of the class described comprising a body in sections, a bracket in the body, having a base provided with pendent flanges, one of which is removably fastened to one section of the body and the other of which fits against and is disconnected from the other section of the body, the bracket having a slot extending through its base and also through both flanges thereof, an actuator comprising a body provided with buttons extending through the first mentioned body, the body of the actuator being fitted in said slot for back and forth movement, and the base being provided with flanges overlying the body of the actuator, a switching member supported by the bracket, for oscillation, a spring connected with the switching member and with the actuator approximately centrally of the length thereof, and means for detachably connecting together the sections of the body of the switch.

In testimony whereof I affix my signature in the presence of two witnesses.

JOHANN G. PETERSON.
